UNITED STATES PATENT OFFICE.

ARTHUR G. LEONARD, ALONZO GRAFFAM, AND BYRON R. WOLCOTT, OF DE KALB, ILLINOIS.

PEGGING-MACHINE.

SPECIFICATION forming part of Letters Patent No. 629,512, dated July 25, 1899.

Application filed November 18, 1898. Serial No. 696,753. (No model.)

To all whom it may concern:

Be it known that we, ARTHUR G. LEONARD, ALONZO GRAFFAM, and BYRON R. WOLCOTT, citizens of the United States, residing at De 5 Kalb, in the county of De Kalb and State of Illinois, have invented certain new and useful Improvements in Pegging-Machines, of which the following is a specification.

Our invention relates to a pegging-machine 10 for pegging boots and shoes, and is shown as embodied in a machine for pegging on a horn after the last is drawn from the boot or shoe to be pegged, although portions of the invention are applicable to machines for pegging a 15 boot or shoe while on the last.

One of the principal features of our invention consists of an improved construction for producing the required horizontal reciprocation of the face-plate of the machine; and 20 our invention is also concerned with other combinations and details of construction, all of which will be fully set out in the annexed claims.

Referring to the accompanying drawings, 25 in which the same letters of reference are used to designate identical parts in all the views, Figure 1 is a side elevation of the complete machine with the framework and the horn-post in section to show the construction. Fig. 30 2 is a rear end elevation of the head of the machine, showing the clutch mechanism. Fig. 3 is a detail view, partially in section and on a larger scale, showing the construction and operation of the hammer-operating 35 mechanism. Fig. 4 is a plan view of the same mechanism. Fig. 5 is a central horizontal sectional view on the line 5 5 of Figs. 1 and 2, but on a larger scale. Fig. 6 is a vertical sectional view on the line 6 6 of Fig. 40 5; and Fig. 7 is a sectional view on the line 7 7 of Fig. 5, showing the cam-disk for operating the peg-driving mechanism and the reciprocating face-plate.

A represents the main frame of the machine, 45 which is of the general shape shown and is supported upon the base B, to which it is connected by bolts or otherwise, as may be desired. The upper portion thereof is of the substantially tubular shape shown and is 50 adapted to receive the tubular lower end of the

adjustable supporting member C. The upper portion of the frame A is slotted, and the screw-bolts D, passing through lugs on either side of the slot, are arranged to contract the upper end to clamp the support C in the customary manner. The upper end of the support C terminates in the flange-plate E, upon which the main frame F of the head is mounted to be adjustable longitudinally and held in place by the bolts G. The driving-shaft 60 H is mounted in the bearings J and K, which are formed integral with or otherwise suitably secured to the main frame F of the head. The driving-pulley L, with its accompanying loose pulley M, is loosely mounted on the shaft 65 H and has an annular channel N formed in its rear face, in which channel a hardened flanged disk O is secured by means of the bolts P. This disk O has the notch Q therein, which is formed with the square shoulder on one side 70 and the somewhat gradual slope on the other side. The shaft H has splined on its rear end the sleeve R, which has pivotally mounted thereon the yoke S, (see Fig. 2,) which terminates in the stud T, which co-operates with the 75 notch Q. The sleeve R has formed upon or fastened to its outer end the lug or arm U, and a helical expanding-spring V is interposed between the lug or arm U and the yoke S to hold the stud T in engagement with the notch Q. To 80 disconnect the clutch and stop the machine, we provide the treadle W, pivoted to the base B and having the link X, extending substantially vertically upward through the tubular portion of the support C to the arm Y, which 85 is fastened to the rock-shaft Z, which is supported in a suitable bearing formed in one side of the support C. The rock-shaft Z has rigidly connected therewith the arm A', (see Fig. 2,) which has its upper end curved, so 90 as to extend around the flanged disk O, and which terminates in an outwardly-beveled point B' and a square shoulder C'. A coiled spring D' or some other spring of a suitable form holds the treadle W normally upward, 95 with the curved portion of the arm A' resting against the flange of the disk O. In a position of rest the stud T, forming the end of the yoke S, is cammed outward by the beveled point B' and rests against the shoulder 100

C', so that it is carried out of connection with the notch Q on the flange of the ring O, and the shaft is held from movement. When the treadle W is depressed to start the machine, 5 the arm A is drawn away from the flange of the disk O and the stud T is permitted to engage with the square shoulder of the notch Q under the stress of the spring V, and the shaft will be carried with the rotation of the 10 driving-pulley until the treadle W is released, when the arm A', swinging into position, will cause the stud T to be cammed outward to release it from the clutch and to stop it from further movement by reason of its contact 15 with the shoulder C'.

The horizontal reciprocation of the face-plate E' is effected by the following mechanism: Rigidly fastened on the shaft H is the cam-disk F', which has formed therein the cam- 20 groove G'. In this cam-groove is located the antifriction-roller H', which is loosely mounted on the bearing-stud J', forming the end of the lever K'. This lever K' has pivoted at its other end the arm L', which is of the shape 25 best shown in Fig. 5, and is screwed or otherwise rigidly fastened to the face-plate E'. The fulcrum of the lever K' is adjustable to furnish the necessary adjustment for the 30 length of the stroke of the face-plate and is constructed as follows, especial reference being had to Fig. 6: The fulcrum M' has its upper and lower ends screw-threaded to receive nuts, and the lower portion N' thereof is squared to fit the longitudinal rectangular 35 slot O', formed in the base-plate F of the head of the machine. A flange P' above the square portion N' serves to support the rectangular block Q', which is mounted to swing upon the round upper portion R' of the fulcrum 40 M'. This squared or rectangular block Q' is mounted in the longitudinal rectangular channel S', formed in the lever K'. It will be seen that as the end of the lever carrying the anti-friction-roller H' is vibrated by means of the 45 cam-groove G' the other end will be vibrated in the opposite direction, the squared bearing-block Q' swinging about the portion R' of the fulcrum as an axis. The nut T', which 50 can be manipulated through the aperture U' in the base-plate F, serves to clamp the fulcrum in any desired position of adjustment to vary the horizontal movement of the face-plate. The nut V' and the washer W' serve 55 to hold the squared bearing-block Q' in position. The vertical reciprocation of the awl bearing-block X' in the face-plate is accomplished by the eccentrically-mounted anti-friction-roller Y' on the enlarged head Z' of the shaft H, which antifriction-roller co-operates with the horizontal slot A' formed in 60 the face of the awl bearing-block X'.

To reciprocate the hammer B', we provide the following mechanism, especial reference being had to Figs. 3 and 4: The cam-disk F' has on its periphery a cam-lug C', which occupies about sixty degrees of said periphery and is arranged on a constant curve, so as to

raise the antifriction-roller D', co-operating therewith, uniformly while the cam is in operation. This antifriction-roller D' is mounted 70 upon a circular bearing-stud E', formed on the rock-shaft F', which is mounted in the trunnions G', formed in the arms H', projecting rearwardly and upwardly from the angular plate J', screwed or bolted onto the base-plate F. The rock-shaft F' has rigidly fastened thereto the arm K', which terminates in a yoke L', in which is pivotally mounted in suitable bearings the rectangular block M', which reciprocates back and forth in the 80 elongated rectangular aperture N', formed in the enlarged upper end O' of the hammer B'. The length of the block M' as compared with the width of the head O' of the driver B' is sufficient to permit of the horizontal reciprocation of the face-plate, with which the driver B' moves, to occur without disturbing the connections between the lever K' and the driver B'. The plate J' has formed thereon or affixed thereto the cup-shaped projection 85 P', which has an aperture Q' in its bottom. The lever K' has formed therein directly above the cup P', when the lever K' is horizontal, a corresponding cup R', which has an aperture in its otherwise closed upper end. 90 A bolt S', which has a head T' at its lower end, passes through the apertures in the cups P' and R' and is encircled by the strong expanding helical spring U'. The upper end of the bolt S', projecting above the cup R', is furnished with a nut and a lock-nut, by which the position of the lever K' can be regulated 95 as may be desired. Owing to the high rate of speed at which the machine is operated, the periphery of the cam-wheel F', which is rotating rapidly, would impart an extremely high rate of revolution to the antifriction-roller D'. In practice we adjust the nut and lock-nut on the bolt S' so that the antifriction-roller D' is just clear of the periphery of 100 the cam-disk F' on its circular portion. This takes the strain and friction off of the roller D' and to a certain extent off of the lever K', except during the actual time that the cam is operating upon it. The coiled spring U' 105 serves to hold the lever K' in its uppermost position and also cushions it in its downward movement. If desired, cushioning washers V', of leather, rubber, or other suitable material, may be placed upon the head T' of the bolt S' to cushion the impact of the head T' with the under side of the cup P' when the lever K' returns to its uppermost position under the impulse of the spring U', when the cam ceases to act. To cushion the downward 110 movement of the lever K' and to provide a positive stop therefor, we fasten to the under side thereof in any desired manner the plate W', which co-operates with cushioning material X', such as leather or rubber, which is 115 placed in the cup-shaped head Y' of the bolt Z', screw-threaded in an aperture A' in the base-plate F of the head of the machine. This screw-threaded bolt furnishes a fine ad- 120

justment for the buffer and stop and secures it in its adjusted position. We furnish it with a flange B^3 , which has a series of notches C^3 therein, with one of which a tooth D^3 , which is fastened by screws to the plate J^2 , coöperates.

The knife operating in the tip of the horn E^3 is substantially the same as that shown in our prior application referred to and need not be further described. The horn E^3 is of the customary shape and has its lower end open and formed with the sleeve F^3 , the lower end of which rests on the shoulder G^3 , formed by the reduced upper portion of the tubular horn-post H^3 . The bore of this sleeve is somewhat larger than the diameter of the co-operating portion of the horn-post, and the set-screws J^3 , which serve to clamp the horn upon the horn-post, may be thus used to regulate the position of the horn relative to the horn-post, thus furnishing any adjustment that may be found necessary to aline the aperture in the horn with the awl and hammer. The shank K^3 of the knife is connected by the short lever L^3 with the upper end of the knife-actuating rod M^3 . To permit of the necessary rotation of the horn without affecting the connections between the lever L^3 and the rod M^3 , we make the lever L^3 double or form one end thereof in a yoke, which has pivotally connected thereto the short sleeve N^3 , which is held between the nut O^3 on the rod M^3 and the nuts and lock-nut on the upper end of the rod. To permit of ready access to these connections for adjustment or otherwise, we construct the cap P^3 of the shape shown in the sectional view in Fig. 1, which rests upon the upper end of the sleeve F^3 . The framework A has formed therein the circular recesses Q^3 and R^3 , in which are mounted the bearing-cups S^3 and T^3 . The sleeve H^3 has fastened thereto the coöperating cones U^3 and V^3 , and the bearing-balls are disposed between these cones in the customary manner. The sleeve H^3 has also fastened thereon the bearing-sleeve cup W^3 , which has coöperating therewith the cone X^3 , which is loosely mounted upon the sleeve H^3 and is held upward to coöperate with the cone W^3 by means of the strong helical expanding-spring Y^3 , which rests upon the shoulder formed by the upper side of the recess R^3 . The lower end of the sleeve H^3 has swiveled thereon the block Z^3 , which has projecting downward therefrom the links A^4 , which are connected to the treadle B^4 , so that when it is desired to depress the horn the downward pressure of the lever B^4 will move the horn downward against the stress of the spring Y^3 . The details of the knife-actuating mechanism in addition to those already described are as follows: Just adjacent to the cam-wheel F' is another cam-wheel C^4 , which has a cam-groove D^4 in its rear face, in which is mounted the antifriction-roller E^4 upon the stud formed on the lever F^4 , which is pivoted, as seen at Fig. 5, at one side of the base-plate

F of the head. This lever F^4 has pivotally connected thereto a link G^4 , which extends down to the bell-crank lever H^4 , to which it is connected, which is mounted in the support J^4 , connected to the base B of the machine. Suitable turnbuckles K^4 are employed to adjust the length of the link G^4 as may be necessary to secure the exact action of the knife required. The bell-crank lever H^4 has its lower arm arranged with several holes, so that the thrust rod or tube L^4 , pivotally mounted thereon, may be adjusted as may be found necessary. The other end of this thrust-rod L^4 is pivotally mounted to the lower arm of a similar bell-crank M^4 , mounted in a yoke N^4 , which projects downwardly from the swivel-block Z^3 previously referred to. This bell-crank M^4 is also arranged to permit of the adjustment of the thrust-rod, and its horizontal arm is connected by a swivel O^4 with the rod M^3 previously referred to. As will be readily seen, this construction of the connections between the driving-shaft and the knife permits of the actuation of the knife entirely unaffected by any change in the vertical or angular position of the horn. The arrangement of the bell-cranks H^4 and M^4 as shown is of importance, as it enables us to get the links G^4 and M^3 sufficiently close together so as not to make the machine cumbersome and at the same time enables us to lengthen out the thrust-rod L^4 , so that any angular variations in the direction thereof caused by the vertical movement of the horn will not affect the position of the knife.

While we have shown our improvements as embodied in a machine of the type shown in our application Serial No. 610,323, filed October 28, 1896, we do not intend that these improvements shall be limited to that particular type of machine when they can be used elsewhere. Moreover, we have not in the present application claimed any features which are disclosed in the prior application, which is for an entirely distinct and independent invention.

While we have shown our invention as embodied in the form which we at present consider best adapted for carrying out its object, yet it will be understood that we do not desire to be limited exactly to the particular forms shown and described, but only so much as may be necessitated by the state of the art and the terms of the following claims.

We claim—

1. In a machine of the class described, the combination of the driving-shaft having the cam-disk thereon, with the lever pivotally mounted adjacent thereto and having the antifriction-roller journaled on one end and co-operating with the periphery of the cam-disk, a driver located in proximity to the other end of said lever and arranged to be reciprocated thereby, and connections between said lever and driver comprising the head O^2 of the driver containing the horizontally-elongated slot N^2 through which passes a cross-piece M^2

rectangular in cross-section and pivotally mounted in the widened yoke L^2 constituting the end of the lever, so as to permit the lateral movement of the driver, substantially as 5 and for the purpose described.

2. In a machine of the class described, the combination of the driving-shaft having the cam-disk thereon, with the lever pivotally mounted adjacent thereto and having one end co-operating with the periphery of the cam-disk, a driver positively connected to the other end of said lever and arranged to be reciprocated thereby, a helically-coiled cushioning and return spring interposed between the lever and its support and a rod between the lever and support limiting the movement of said lever away from the support, substantially as described. 15

3. In a machine of the class described, the combination of the driving-shaft having the cam-disk thereon, with the lever pivotally mounted adjacent thereto having one end co-operating with the periphery of the cam-disk and having a recess in its side, a supporting-frame having a recess therein opposite the recess in the lever, a driver positively connected to the other end of said lever and arranged to be reciprocated thereby, a coiled expanding cushioning and return spring having its ends in the aforesaid recesses, and connections between the lever and its supporting-frame to limit the movement of the lever, substantially as described. 25

4. In a machine of the class described, the combination of the driving-shaft having the cam-disk thereon, with the lever pivotally mounted adjacent thereto having one end co-operating with the periphery of the cam-disk and having a recess in its side, a supporting-frame having a recess therein opposite the recess in the lever, a driver positively connected to the other end of said lever and arranged to be reciprocated thereby, a coiled expanding cushioning and return spring having its ends in the aforesaid recesses, and a rod between the lever and support for limiting the movement of the lever relative to its support. 45

5. In a machine of the class described, the combination of the driving-shaft having the cam-disk thereon, with the lever pivotally mounted adjacent thereto having one end co-operating with the periphery of the cam-disk and having a recess in its side, a supporting-frame having a recess therein opposite the recess in the lever, a driver positively connected to the other end of said lever and arranged to be reciprocated thereby, a coiled expanding cushioning and return spring having its ends in the aforesaid recesses, and a headed rod passing through the lever and the support and having nuts thereon whereby the movement of the lever relative to the support may be limited as desired. 60

6. In a machine of the class described, the combination of the driving-shaft having the cam-disk thereon, with the lever pivotally

mounted adjacent thereto and having one end arranged to co-operate with the periphery of the cam-disk, a driver positively connected 70 to the other end of said lever and arranged to be reciprocated thereby, and means for adjusting the position of said lever so as to prevent frictional contact of its end with the co-operating cam-disk except when the cam is in operation, comprising a headed bolt or rod passing through apertures formed in the lever and its support between the fulcrum and the driver, and set-nuts on said bolt, substantially as described. 80

7. In a machine of the class described, the combination of the driving-shaft having the cam-disk thereon, with the lever pivotally mounted adjacent thereto and having one end arranged to co-operate with the periphery of 85 the cam-disk, a driver positively connected to the other end of said lever and arranged to be reciprocated thereby, and means for adjusting the position of said lever so as to prevent frictional contact of its end with the co-operating cam-disk except when the cam is in operation comprising a bolt located adjacent to the lever and having nuts thereon arranged to contact and co-operate with the lever to hold it in any desired position of adjustment. 90

8. In a machine of the class described, the combination of the driving-shaft having the cam-disk thereon, with the lever pivotally mounted adjacent thereto and having its end 100 co-operating with the cam portion of said disk, a reciprocating face-plate with the driver movable therein, and positive connections between the other end of said lever and the driver permitting the reciprocation of the 105 driver by the lever undisturbed by the reciprocating movement of the face-plate but compelling the positive movement of the driver with the lever in both directions. 110

9. In a machine of the class described, the combination of the driving-shaft having the cam-disk thereon, with the lever pivotally mounted adjacent thereto and having one end co-operating with the cam portion of said disk, a reciprocating face-plate with a driver 115 mounted therein and reciprocating at right angles to the reciprocation of the face-plate, and connections between said driver and the other end of the lever comprising a longitudinal slot in the head of said driver, and a block pivotally mounted on the end of said lever and sliding in the slot in the head of the driver, and having sufficient length to permit of the necessary movement of the driver relative thereto caused by the reciprocation of 125 the face-plate. 120

10. In a machine of the class described, the combination of the driving-shaft having the cam-disk thereon, with the lever pivotally mounted adjacent thereto and having an anti-friction-roller journaled on one end thereof and co-operating with the periphery of the cam-disk, a driver operatively connected to the other end of said lever and arranged to be 130

reciprocated thereby in both directions, and means for adjusting the position of the lever to prevent operative contact between the anti-friction-roller and the periphery of the cam except when the cam is in action, comprising a headed bolt loosely passing through apertures in the lever and its support between the fulcrum and the driver, and provided with nuts for regulating the operative length of the bolt.

11. In a machine of the class described, the combination with the driving-shaft having a cam-disk thereon, of a reciprocating face-plate, a lever having one end coöperating with said disk and the other end pivotally connected to said face-plate and a fulcrum for said lever on which it may turn and slide, substantially as described.

12. In a machine of the class described, the combination with the driving-shaft having a cam-disk thereon, of a reciprocating face-plate, a lever having one end coöperating with said disk and the other end pivotally connected to said face-plate, a fulcrum for said lever on which it may turn and slide, and means for adjusting the fulcrum longitudinally of said lever.

13. In a machine of the class described, the combination with the driving-shaft having a cam-disk thereon, of a reciprocating face-plate, a lever having one end coöperating with said disk and the other end connected to said face-plate, and a fulcrum on which said lever may turn and slide, said fulcrum being adjustable longitudinally of said lever.

14. In a machine of the class described, the combination with the driving-shaft having a cam-disk thereon, of a reciprocating face-plate, a lever having one end coöperating with said disk and the other end connected to said face-plate, a fulcrum on which said lever may turn and slide, said fulcrum being adjustable longitudinally of said lever and comprising the bolt M' having the squared portion N' coöperating with the slot O', and the round portion R' carrying the square bearing-block Q' coöperating with the longitudinal rectangular slot S' in the lever.
